COMMUNICATION SIGNALING SYSTEM

Application filed June 30, 1930. Serial No. 464,961.

This invention relates to signaling systems for use in cable, radio or land-line telegraphy or in the combined use of any of these means of communication. The object 5 of the invention is directed particularly toward improvement in the transmitting and receiving instruments and in the adaption of the same for more clearly communicating messages and avoiding the effect of line 10 interference.

A further object is to provide simpler equipment at repeating stations for land lines over which cable code messages may be relayed, thus rendering it easier to maintain. 15

In the use of repeating equipment, particularly where messages have to be relayed from a cable to a land line or vice versa, difficulties have frequently been encountered in the 20 maintenance of proper adjustments of the relays themselves so that they will not be subject to extraneous line interference. One of the principal reasons for this is that in the well-known cable code it is the practice to 25 employ time intervals of zero line potential between the signaling impulses for each letter and longer time intervals of zero potential between the words. Thus, the cable-code is usually made up of three elements or kinds 30 of signals—positive for dots, negative for dashes and zero for letter and word spaces. The zero elements are particularly susceptible to destructive interference, a fact which was realized in the early stages of telegraphy 35 so that on land lines the difficulty was overcome by the use of polar methods instead of the “open and closed” method.

The present invention provides a means for utilizing the almost universally adopted cable-code while eliminating its objectionable intervals of zero line potential and substituting a line condition which is distinguishable from the dot and dash signaling impulses but which at the same time tends to minimize interference effects.

In carrying out this invention the communications circuit has impressed upon it the usual cable code signals consisting of positive and negative impulses and where letter or word spaces are required an alternating

current of suitable frequency is used in place of the zero potential.

Several alternative embodiments of the invention are diagrammatically illustrated in the accompanying drawings in which 55

Fig. 1 shows the usual cable-code transmitter with circuits adapted to the purpose of this invention.

Fig. 2 shows two graphs of line signals one according to past practice, the other as modified by this invention. 60

Fig. 3 shows a method of receiving the signals and mechanically filtering out the frequency which would be used in place of zero potential. 65

Fig. 4 shows electrical filter arrangement alternative to that shown in Fig. 3.

Fig. 5 shows an adaptation of this invention to the requirements of a repeater station. 70

Fig. 6 shows a repeater station adaptation alternative to that shown in Fig. 5.

In the various embodiments of this invention a similar method of modifying the transmitted signals will be apparent. The essence of the invention is more in the method than in the means employed. In fact it has been discovered that new and advantageous results are obtainable from certain minor adjustments which can be made on transmitting and receiving equipment of the well-known types. More particularly is this true in respect to the use of the standard Gulstadt arrangement for transmission, as will be more clearly brought out in this specification. 75

In Fig. 1 the transmitter is shown. In this case it comprises two relays 1 and 2, relay 1 having three windings 3—4, 5—6, and 7—8, and relay 2 having a winding 16—17. The usual method of transmission is to apply positive potential to the transmitting contact 18 for a dot signal and to the contact 19 for a dash signal. When the impulse is taken at contact 18 there follows a drop of potential in winding 3—4 from terminal 3 to terminal 4, this causing the armature tongue 11 to move against contact 12. Positive potential is thus applied from the source 20 through resistance 10 to terminal 6 of winding 6—5; also to terminal 7 of winding 7—8. The energizing 80

forces of these two windings oppose one another during the moment that condenser 9 receives a charge. After that, the winding 6-5 remains energized in opposition to the force of winding 3-4 and when the latter is de-energized the winding 6-5 first acts alone in breaking contact between armature 11 and contact 12, then its force is boosted by the series connection with winding 8-7, both windings receiving the discharge of the condenser 9 and passing the same through the resistance 15 and conductor 18 back to the opposite side of the condenser. The result is that the motion of armature 11 is considerably accelerated at the end of a dot or dash signal, or when the winding 3-4 receives a reversal of current.

The operation of the relay 1 when a dash signal is to be transmitted is brought about by impressing positive potential on the contact 19, in which case the movement of armature tongue 11 is against contact 18 and all the actions and reactions of the windings 3-4, 5-6, 7-8 and condenser 9 are just reversed from those in effect in the transmission of a dot signal.

Following this arrangement further, it will be seen that relay 2 is controlled by relay 1 in this manner: if one or more successive dot signals are to be transmitted, current flows from the positive pole of the source 20 through contact 12, armature 11 and resistance 14 to terminal 16 of the winding in relay 2, thence back to the neutral pole of source 20. Relay winding 16-17 when energized by current in this direction throws its armature 21 against contact 22, thus feeding positive potential to the line or cable 24, the neutral potential being permanently grounded at 25. This is the usual practice in transmitting a positive impulse to represent a dot and a negative impulse to represent a dash. The ordinary transmitting device, however, is somewhat different from that shown in Fig. 1 in that provision is made for space signals during which zero-potential is applied to line 24.

It has been the common practice heretofore in operating repeater stations to provide pulsating regenerators sensitive to the incoming signals and adapted to definitely time the duration of the repeated signals. Thus the regenerator has a natural beat frequency corresponding with the signaling unit. The Gulstadt device is so used in land-line telegraphy to provide a natural beat frequency equal to the unit signal frequency, and to minimize the travel time of the relay armatures by the use of a condenser and resistance of suitable values in series respectively with the relay windings.

The present invention makes use of a new practice in the employment of such values for the resistance 15 and the condenser 9 that a current of greater frequency than the dot and dash signaling frequency will be set up

on the line during the lapse of a space signal. The operation is as follows:

A relatively small capacity value for condenser 9 and a relatively low resistance 15 are chosen. During a space signal when no current is flowing through winding 3-4, the condenser 9 charges and discharges rapidly as compared with the time constants of the dot and dash signals. The condenser charge is continually reversed by the vibration of armature 11 between the contacts 12 and 13 which are connected respectively to opposite poles of the source 20. The relay armature 21 is caused to vibrate in synchronism with armature 11, since the winding 16-17 of relay 2 receives part of the current flow in either direction through armature 11. In fact, if it were not necessary to employ a different voltage for source 20 as compared with the line voltage, then relay 2 might be eliminated entirely and the signals could be transmitted directly to the line 24 from source 20 through armature 11.

In the operation of this invention, the space signaling frequency is interrupted by closing either of the contacts 18 or 19 against the positive source of potential to transmit dot or dash signals. It is obvious that the energizing effect of a current flow through winding 3-4 can be made to suppress the frequency set up in windings 5-6 and 7-8. Hence, this arrangement has no disturbing effect upon the operation of the transmitter in sending dot and dash signals.

Comparison of line signals according to past practice and as obtained in the employment of this invention may be observed in the two graphic representations of signals shown in Fig. 2. In both graphs the dot signals are indicated at A and dash signals at B. The positive pulse C represents three dots in succession. At D a short spacing signal occurs as between letters and at E a longer spacing signal as between words. The zero line potential of these spacing signals D and E is replaced in the other graph by an alternating current condition as at F. The idea of impressing this frequency on the line automatically whenever there is a pause in the transmission of dots and dashes constitutes the essence of this invention.

Receptive means are shown in Fig. 3 for recording the dot and dash signals and filtering out the space signals of higher frequency. The line 24 is connected to relay winding 27, the other side of which is grounded. The relay armature 28 responds to each of the three elements of the signals, dots, dashes and spaces, vibrating rapidly on reception of the latter. The recorder coil 29 is tuned by adjusting the stiffness of its suspension so that it will respond to the fundamental signal frequency of the dots and dashes only. This coil derives its energy from the source 32 and obviously the two-

directional circuit is established by the vibration of armature 28 to and fro between contacts 33.

Fig. 4 shows an electrical filter which consists of two inductances 30 connected in series, with their centre points connected through a condenser 31 to mid-point of the energizing source 32. Between the points R. R. of the output circuit either a recorder 29 or a repeater relay may be connected. The impedance of coils 30 acting in conjunction with the condenser 31 filters out the space signaling frequency such as might be used preferably on a land line. Thus, in the output circuit which might be connected to a cable the condition of zero line potential for space signals would be automatically restored.

Fig. 5 shows re-transmitting relays 34 and 35 connected between the points R. R. of the output circuit which otherwise is the same as shown in Fig. 4. The filtering out of alternating current for space signals takes place through the inductances 30. Relay 34 being polarized responds only to dash signals and relay 35 only to dot signals. Their armatures 36 and 37 are shown in the neutral position when zero potential is impressed upon the line. Upon reception of a dot signal over line 24, armature 28 swings against the positively-poled contact 33, relay 35 operates to throw its armature 37 against contact 38 to ground the negative side of the battery 39. Positive battery already connected to the cable 40 through relay armature 36 provides the positive impulse required for a dot signal. Relay 34 operates similarly to transmit a dash signal.

Fig. 6 shows the filtering effect of two slow-acting relays 41 and 42, one for dash signals and one for dot signals. These are so adjusted that they will not respond to the high vibrating frequency but respond perfectly to the low signaling frequency. This circuit may also be used at a repeater station between a land line and a cable.

It is obvious that communications received over a cable in cable code (that is, with zero potential signals for spaces) can be translated into the modified cable code with high frequency space signals for transmission over land lines, use being made of the transmitting means similar to that shown in Fig. 1. In this case it will be understood that the signals received over the cable would be utilized to actuate two relays one for closing contacts as at 18 to transmit a dot and the other for closing contacts as at 19 to transmit a dash.

What is claimed is:

1. In a communications system the method of code transmission which consists in impressing upon the transmitting medium at a predetermined basic frequency a series of intelligence bearing signals separable by but not overlapped by non-intelligible spacing signals of a different frequency.

2. In a communications system means to codify the intelligence to be transmitted from one station to another which comprises two signal-element initiators, one for signals of dot-significance, the other for signals of dash-significance, and means rendered operative when neither dot nor dash is being signaled to maintain a third signal-element as a preventer of interference effects between the two stations.

3. In a communications system a transmitter comprising means to impress intelligence bearing signals upon a circuit at a predetermined basic frequency, and means to maintain the circuit unimpaired by extraneous interference during intervals between said signals by impressing upon the circuit a current of another frequency, the units of which are non-intelligible.

4. In a communications system, a transmitter comprising a plurality of contact points each for initiating a distinctive signal, a relay including a plurality of energizing coils, one of said coils being connected with said contact points, two other coils being in series in a closed circuit which includes a resistance and a condenser, connections at the mid-point between these two coils through the relay tongue and its contacts with opposite poles of an energy source, a shunt circuit including a second relay coil between said relay tongue and a neutral tap from said energy source, and means to adjust the timing characteristics of the said condenser and resistance to a frequency different from the basic signaling frequency.

5. In a communications system, a telegraph circuit, means to impress upon said circuit successively a basic signaling frequency and a non-intelligible spacing frequency and receptive means comprising a filter to suppress the spacing frequency.

6. In a communications system a receiving relay comprising connections between a source of energy and the contact points associated with the relay armature tongue; an output circuit which includes the relay armature tongue, a filter, a recording or repeating instrument and a neutral point tap from said source of energy; and means to adjust the recording or repeating instrument to render it responsive to a predetermined basic signaling frequency and non-responsive to a non-intelligible spacing frequency intermittently received by said relay.

7. In a communications system a receiver responsive to intelligence-bearing signals transmitted at a single predetermined basic frequency, a filter adapted to suppress all spacing signals of a different frequency, intermittently transmitted, and a regenerative instrument adapted to repeat only the intelligence-bearing signals.

8. In a communications system a receiver responsive to intelligence-bearing signals

transmitted at a predetermined basic frequency and separated by spacing signals of zero potential, a telegraph circuit and means to impress upon the same a regeneration of said intelligence-bearing signals separated by non-intelligible spacing signals of a frequency other than the said basic frequency.

9. In a communications system repeating equipment comprising a receiving relay, a filter for suppressing other than intelligence-bearing signals, a plurality of repeating relays each responsive to a predetermined signal characteristic and means employed upon reception of intelligence-bearing signals such as are separated by spacing signals of other than zero-potential-characteristic to retransmit only the intelligence-bearing signals.

10. In a communications system, means for translating the zero units in a three-element code into a series of positive and negative units of shorter duration than the other signaling elements of said code.

11. In a communications system, the method of eliminating interference effects therein comprising impressing positive, negative and zero signaling units on the line and transforming the zero units into a series of positive and negative units of shorter duration than the other signaling units.

12. In a communications system, means for translating the zero elements in a three-element code into a series of positive and negative units of shorter duration than the other signaling units of said code, and means for re-translating said positive and negative units into zero elements.

13. In a communications system, the method of code transmission comprising impressing upon the transmitting medium in any desired order but at a predetermined basic frequency positive and negative signal units separable by but not overlapped by a series of alternate positive and negative units of a different frequency.

In witness whereof, I hereunto subscribe my name this 26th day of June, 1930.

MARION H. WOODWARD.
